CLAIM

The ornamental design for a low-voltage up-light, as shown and described.

DESCRIPTION

FIG. 1 is a front perspective view of the low-voltage up-light showing the new design;

FIG. 2 is a rear perspective view thereof;

FIG. 3 is a top view thereof;

FIG. 4 is a left side view thereof;

FIG. 5 is a bottom view thereof;

FIG. 6 is a right side view thereof;

FIG. 7 is a rear view thereof; and,

FIG. 8 is a front view thereof.

The broken lines shown on the drawings depict portions of the low-voltage up-light that form no part of the claimed design.
